UNITED STATES PATENT OFFICE.

CYRUS HUSSEY, OF TOLEDO, OHIO, ASSIGNOR TO THE TOLEDO MOULDING COMPANY, OF SAME PLACE.

DESIGN FOR A CURTAIN-POLE.

SPECIFICATION forming part of Design No. 22,078, dated December 20, 1892.

Application filed May 24, 1892. Serial No. 434,238. Term of patent 14 years.

To all whom it may concern:

Be it known that I, CYRUS HUSSEY, a citizen of the United States, residing at Toledo, in the county of Lucas and State of Ohio, 5 have invented and produced a new and original Design for Curtain-Poles, of which the following is a specification, reference being had to the accompanying drawings, showing a part thereof.

10 Figure 1 is a front elevation of the curtain pole showing my design. Fig. 2 is a cross sectional view on lines $x-x$ Fig. 1, enlarged to more fully disclose the design of the same.

15 The leading feature in my design consists in a pole having its entire surface ornamented by a series of longitudinal scallops or flutes extending its entire length and entirely surrounding the pole.

In the drawings 1 indicates the pole, and 3

the longitudinal scallops or flutes. These 20 scallops extend the entire length of the pole, are of uniform size, and being quite narrow give the pole a milled appearance. The pole is also of uniform diameter. The pole thus ornamented is used as a curtain pole and presents a pleasing and unique appearance. 25

Having thus described my invention, what I claim is:—

30 The design for a curtain pole, substantially as shown and described.

In testimony that I claim the foregoing as my own I hereby affix my signature in presence of two witnesses.

CYRUS HUSSEY.
